UNITED STATES PATENT OFFICE.

WILLIAM M. JOHNSON, OF URBANA, OHIO, ASSIGNOR TO THE W. H. MARVIN COMPANY, OF URBANA, OHIO, A CORPORATION OF OHIO.

CARTON.

Application filed March 23, 1927. Serial No. 177,720.

This invention relates to cartons made from a single blank of card board.

One of the objects of the invention is to provide a carton, the cross sectional shape of which will be in the form of a right-angled triangle which will enable the carton when packed with commodity to be readily nested for shipping purposes.

A further object of the invention is to provide a carton of the character described having the side with the largest area provided with a transparent window to display the commodity contained in the carton.

A further object of the invention is to provide a blank so scored as to form the three sides and the ends of a carton of triangular shape, with means for locking the same in folded position so as to provide a blank which is easily and readily folded to form a carton of durable character which will retain its triangular shape in usage.

A further object of the invention is to provide a carton which will be simple in construction, economical in manufacture and effective for the purposes for which it is designed; further objects appearing from the accompanying description, claim and statement of advantages.

In the accompanying drawing:

Fig. 1 is a plan view of a blank from which the carton is formed.

Fig. 2 is a front elevation.

Fig. 3 is a bottom plan.

Fig. 4 is an end elevation.

Fig. 5 is a section on the line A—A of Fig. 2.

Referring to Fig. 1, the blank is scored as indicated in dotted lines to form a rectangular shaped front section 1, a rectangular shaped back section 2, a rectangular shaped bottom section 3, a second bottom section 4, triangular shaped end sections 5, additional triangular shaped end sections 6, and locking flaps 7 projecting from the sections 6. Each of the sections 5 and 6 is a right-angled triangle, with the altitude of each triangle 5 attached to the back 2 and the hypotenuse of each triangle 6 attached to the front 1. The bottom section 3 is provided with slits 9, and the section 4 is cut to form tongues 8. The front section 1 is cut away to form a window 10 which is closed by a sheet 11 of transparent material, the edges of which are pasted to the inner surface of section 1 about the opening there-

in. In folding, the end sections 6 are folded against the outside of the end sections 5, the section 4 folded against the under side of the bottom section 3, with the flaps 7 lying on the upper side of the bottom section 3, after which the tongues 8 are inserted in the slits 9.

This results in a carton in the form of a plain right-angled isosceles triangle, the bottom sections 3 and 4 forming the base, the back section 2 forming the altitude and the front section 1 the hypotenuse. It will be observed that the window is placed in that part forming the hypotenuse so that the window will be on that side of the box which has the greatest area and which gives therefore the greatest display space. Further, by forming the carton in this manner, the cartons may be readily nested when filled with the commodity by placing the front or hypotenuse sides of two cartons face to face. The transparent material employed is preferably a material known as cellophane which is not only very transparent, but also easily torn away to thereby furnish access to the goods packed in cartons so that the purchaser may remove the goods as needed without unfolding the carton. Such a carton is particularly intended for packing dates and the like for use as a confection which makes the advantage of the last feature apparent.

By forming the blank in the manner described, a very strong and durable carton is provided which will hold its shape when filled with the commodity and which will stand a maximum amount of usage.

The shape and construction of the blank, not only provides a carton which has a large capacity and nesting facilities for packing purposes, as well as a large display side to display the contents to the buying public, but also when the carton is on display no locking flaps are visible because of the fact that they are on the bottom of the carton, thus making a carton for display purposes which is attractive in appearance and pleasing to the eye.

Having thus described my invention, I claim:

In a carton, a blank formed to provide a triangular shaped carton which is in cross section the shape of a plane right-angled, isosceles triangle, said blank having a rectangular shaped section to form the front,

another rectangular shaped section to form of said back section, and another section
the back, and a third rectangular shaped section to form the bottom, said front section
being of greater width than the other sections
5 and provided with a transparent window, said front section being provided at
each end with a triangularly-shaped section
of right-angled form attached to said front
section along the line of its hypotenuse, a
locking flap projecting from one of the sides
10 of each of said triangular shaped sections,
said back section also having at each end a
triangular shaped section attached thereto
along the line of its altitude with the base
15 thereof co-extensive with the adjacent side

attached to said front section adapted to
overlie the bottom section and be interlocked
therewith, the triangular sections which are
attached to the front section being adapted 20
to overlie the outer side of those triangular
sections which are attached to the back sec-
tion so as to form the ends of the carton
when folded, the rectangular shaped locking
flaps projecting inwardly parallel with said 25
bottom sections.

In testimony whereof, I have hereunto set
my hand this 21st day of March, 1927.

WILLIAM M. JOHNSON.
